UNITED STATES PATENT OFFICE.

SETH A. WELLMAN, OF MASON CITY, IOWA.

GATE LATCH.

Application filed July 19, 1924. Serial No. 727,067.

To all whom it may concern:

Be it known that I, SETH A. WELLMAN, a citizen of the United States of America, and resident of Mason City, Cerro Gordo County, Iowa, have invented a new and useful Gate Latch, of which the following is a specification.

The object of this invention is to provide an improved automatic latch for swinging gates.

My invention consists in the construction, arrangement and combination of elements hereinafter set forth, pointed out in the claims and illustrated by the accompanying drawing, in which—

Figure 1 is a plan view illustrating a gate equipped with my improved latch. Figure 2 is a side elevation of the same. Figure 3 is a cross-section, on an enlarged scale, on the line 3—3 of Figure 2. Figure 4 is a perspective view of the locking cap detached and in inverted position.

In the construction of the device as shown the numeral 10 designates generally a gate, 25 of any suitable construction, hinged at one end to a post 11 and adapted to be engaged at times at its opposite end with a latch post 12. Extending through and secured firmly in the end bar 13 at the free end of the gate 30 are spaced eyebolts 14, having their eyes in vertical alinement beyond the free end of the gate. Mounted in the eyes of the eyebolts 14, for rotary oscillation and for vertical sliding movement, is a latching rod 15, 35 arranged parallel with the end gate bar 13, and fixed rigidly to said latching rod are latching caps 16, one just above and supported on each of the eyebolts 14. One of the caps 16 is shown in Figure 4, and is 40 formed with a downwardly extending peripheral flange 17 adapted to loosely embrace the eye of a bolt 14, or other suitable bearing member of similar form. The flange 17 is formed with a radial notch 18, relatively deep, adapted to engage the stem of the eyebolt 14 and when so engaged to prevent rotary movement of the cap 16 and the latching rod 15 attached thereto. Fixed to the latching rod 15 and extending therefrom 45 divergently in a general direction away from the gate 10, are wings 19, 20, which wings preferably are curved at their outer ends or flange away from each other more sharply as clearly shown in Figure 3. The wings 19, 50 20, as here shown, are duplicated, one pair

being located near the top and the other near the bottom of the gate. The wings 19, 20 are adapted at times to engage on opposite sides of, and partially embrace the latch post 12, or more specifically in this instance, 60 where the post is shown as of considerable diameter, an auxiliary post or rod 12' supported from and in parallel relation to said post 12, said auxiliary post or rod being of considerably less diameter than the post. It 65 is obvious that the action is the same whether the wings engage the post 12 directly, or an auxiliary member fixed thereto as here shown. When the wings 19, 20 are so engaged, the notches 18 of the caps 16 are in 70 position to engage the stems of the eyebolts 14, thus preventing rotary movement of the rod 15 and effectively latching the gate to the post 12. When the parts are in this position the wings 19, 20 extend in substantially the plane of the gate, the parts being in the position shown in dotted lines in Figure 1. To unlatch the gate, the rod 15 is 75 lifted manually in its bearings in the eyebolts 14 to disengage the notch 18 from the stems thereof, after which said members may be rotated, the rod 15 turning in the eyes of the bolts and the edge of the flange 17 sliding on the stem of the bolt, and the gate may then be swung on its hinges, the 80 wings 19, 20 extending at an angle to the trend of the gate and disengaging from the latch post. As the gate is swung on its 85 hinges away from the latch post 12, the wings 19, 20 naturally turn in such direction 90 that they point toward said post, as shown in Figure 1, so that when the gate is again moved to closed position said wings will engage the post 12 or 12' and be turned by such engagement into a position where they will 95 prevent accidental opening of the gate, the notch 18 coming into engagement with the stem of the eyebolt 14. To insure that the rod 15 and cap 16 will not turn too far, shallow notches 21, 22 are formed in the edge of 100 the flange 17, one on each side of and equally spaced from the latching notch 18, which notches are designed to engage, selectively, the stem of the eyebolt and limit such rotary movement. The shallow notches 21, 22 are spaced from the notch 18 to such extent that in opening movement of the gate, the cap 16 is turned just far enough for one or the other of said notches to engage the stem of the eyebolt as the wings 19, 20 clear 110

the post 12 or 12', and consequently hold said wings in such position that they will engage the post when the gate is swung shut, and by such engagement be moved to latching position. The notches 21, 22 are so shallow that the jar caused by engagement of the wings with the post causes them to be disengaged from the eyebolt, and preferably are rounded so that the cap 16 rides up on the eyebolt when such jar occurs. The notch 18 is deep enough that it will not become engaged except by purposeful lifting of the cap or rod manually. One only of the caps 16 may be used, but if more are employed they must be so arranged that their notches will simultaneously engage the respective eyebolts.

At times if desired the rod 15 may be rotated manually to inoperative position, one or the other of the shallow notches 21, 22 of the cap 16 passing beyond the stem of the eyebolt and the wings 19, 20 passing into a position approximately parallel or in contact with the gate 10, so that the gate will not be latched when closed. It is obvious that the latching means may be mounted on the post 12 and arranged to engage the gate bar 13 if desired.

I claim as my invention—

- 30 1. The combination with a gate hinged for swinging movement relative to a latch post, of a latching device comprising a bearing having a stem by which it is fixed to the free end of said gate, a rod mounted for rotary oscillation and for vertical sliding movement in said bearing, a cap fixed to said rod above said bearing and having a depending peripheral flange, the flange of said cap being formed with a radial notch adapted to receive the stem of said bearing and prevent oscillation of said cap and rod, and divergent wings fixed to said rod

and adapted to partially embrace the latch post at times.

2. The combination with a gate hinged 45 for swinging movement relative to a latch post, of a latching device comprising a bearing having a stem by which it is fixed to the free end of said gate, a rod mounted 50 for rotary oscillation and for vertical sliding movement in said bearing, a flanged cap fixed to said rod above said bearing, the flange of said cap being formed with means to engage the stem of said bearing and prevent oscillation of said cap and rod, 55 divergent wings fixed to said rod and adapted to partially embrace the latch post at times, and means to limit rotary movement of said cap relative to said bearing in both directions from the stem-engaging means. 60

3. The combination with a gate hinged for swinging movement relative to a latch post, of a latching device comprising a bearing having a stem by which it is fixed to the free end of said gate, a rod mounted 65 for rotary oscillation and for vertical sliding movement in said bearing, a flanged cap fixed to said rod above said bearing, the flange of said cap being formed with a relatively deep notch adapted to engage the 70 stem of said bearing and when so engaged to prevent oscillation of the cap and rod, divergent wings fixed to said rod and adapted at times to engage on opposite sides of the latch post, and relatively shallow notches 75 in the flange of said cap, on opposite sides of the first notch, to engage the stem of the bearing at times and prevent accidental oscillation of said cap and the rod.

Signed at Mason City, in the county of 80 Cerro Gordo and State of Iowa, this 5th day of April, 1924.

SETH A. WELLMAN.
